CLAIM

The ornamental design for a LED lamp, as shown and described.

DESCRIPTION

FIG. 1 is front view of a LED lamp, showing one embodiment of my new design;

FIG. 2 is a rear view of FIG. 1;
FIG. 3 is a left view of FIG. 1;
FIG. 4 is a right view of FIG. 1;
FIG. 5 is a top plan view of FIG. 1;
FIG. 6 is a bottom plan view of FIG. 1;
FIG. 7 is a front, top and left side perspective view of FIG. 1;
FIG. 8 is an enlarged view of the portion labeled "A" surrounded in FIG. 7;
FIG. 9 is an enlarged view of the portion labeled "B" surrounded in FIG. 7;
FIG. 10 is a front view of a LED lamp, showing another embodiment of my new design;
FIG. 11 is a rear view of FIG. 10;
FIG. 12 is a left view of FIG. 10;
FIG. 13 is a right view of FIG. 10;
FIG. 14 is a top plan view of FIG. 10;
FIG. 15 is a bottom plan view of FIG. 10;
FIG. 16 is a front, top and left side perspective view of FIG. 10;
FIG. 17 is an enlarged view of the portion labeled "C" surrounded in FIG. 16;
FIG. 18 is an enlarged view of the portion labeled "D" surrounded in FIG. 16;
FIG. 19 is a front view of a LED lamp, showing another embodiment of my new design;
FIG. 20 is a rear view of FIG. 19;
FIG. 21 is a left view of FIG. 19;
FIG. 22 is a right view of FIG. 19;
FIG. 23 is a top plan view of FIG. 19;
FIG. 24 is a bottom plan view of FIG. 19;
FIG. 25 is a front, top and left side perspective view of FIG. 19;
FIG. 26 is an enlarged view of the portion labeled "E" surrounded in FIG. 25;
FIG. 27 is an enlarged view of the portion labeled "F" surrounded in FIG. 25;
FIG. 28 is a front view of a LED lamp, showing another embodiment of my new design;
FIG. 29 is a rear view of FIG. 28;
FIG. 30 is a left view of FIG. 28;
FIG. 31 is a right view of FIG. 28;
FIG. 32 is a top plan view of FIG. 28;
FIG. 33 is a bottom plan view of FIG. 28;

(Continued)

FIG. 34 is a front, top and left side perspective view of FIG. 28;

FIG. 35 is an enlarged view of the portion labeled "G" surrounded in FIG. 34; and,

FIG. 36 is an enlarged view of the portion labeled "H" surrounded in FIG. 34.

The LED lamp is shown with a symbolic break in its length. The appearance of any portion of the article between the break lines forms no part of the claimed design.

The broken line showing in the drawings is included for the purpose of illustrating portions of the LED lamp and forms no part of the claimed design.
